UNITED STATES PATENT OFFICE.

JOHN E. FULLER, OF NEW YORK, N. Y., ASSIGNOR TO HIMSELF AND
SYDNEY B. STARR, OF SAME PLACE.

SAFETY-PIN FOR SCARFS, &c.

SPECIFICATION forming part of Letters Patent No. 617,091, dated January 3, 1899.

Application filed October 8, 1898. Serial No. 692,977. (No model.)

To all whom it may concern:

Be it known that I, JOHN E. FULLER, a citizen of the United States, residing in the city, county, and State of New York, have invented 5 an Improvement in Safety-Pins for Scarfs, &c., of which the following is a specification.

Pins of different characters have been made with a longitudinal slot and a cross-piece in the slot and a connecting pivot-pin, so that 10 after the pin has been thrust through the article the cross-piece will assume a transverse position and prevent the pin being withdrawn. In pins of this character it has been difficult to introduce the pin, because it was usually 15 necessary to hold the cross-piece in position in order that the pin might be thrust through the fabric.

My present improvement relates to the combination, with the pin having a cross-piece, of 20 a sliding collar adapted to hold the cross-piece in position when being inserted, and which collar is pressed back by contact with the fabric as the pin is thrust into position. I also provide a spring by which the cross- 25 piece is thrown out automatically after the ends have entirely cleared the inner side of the fabric.

In the drawings, Figure 1 is an elevation of the scarf-pin, partially in section, to illustrate the sliding collar for holding the cross-piece and the spring for projecting the same when the cross-piece is liberated from the collar. Fig. 2 is a horizontal cross-section of the pin with the cross-piece turned out at right 35 angles to the pin, and Fig. 3 is a section representing the present improvement as applied to a stud with a short stem.

The pin A is to be of suitable size and shape. It is shown in the drawings as magnified and 40 much larger than the usual size for a scarf-pin, and there may be a gem or ornamental head B at the upper end of the pin.

In the body or shank of the pin a longitudinal mortise is provided, and in this mortise 45 a cross piece or bar C is introduced and pivoted at 2, and D is a sleeve or collar fitting around the shank of the pin and adapted to slide endwise freely, so that it may be brought down to confine the upper end of the cross- 50 piece C when that cross-piece is turned into the longitudinal mortise, so that the cross-

piece may not interfere with the insertion of the pin into the scarf or fabric, and this collar D, coming into contact with the surface of the fabric, is held thereby while the pin is 55 pressed on into such fabric, and the cross-piece C, swinging on this pivot 2, assumes a position at right angles, or nearly so, to the pin in order that the pin may not be withdrawn until the cross-piece has been returned 60 to the mortise, so as to coincide longitudinally with the pin. This collar D may be more or less ornamental and form the upper end of the scarf-pin or an ornament thereon adjacent to the jewel B. 65

I find it advantageous to employ a spring E, introduced into the pin, so that it acts against the cross-piece C to throw it out at right angles, or nearly so, to the pin. A convenient way of introducing this spring is to 70 prolong the slot sufficient for the reception of the spring and to allow this spring to act against the upper part of the cross-piece C. Of course this spring is slightly pressed when the cross-piece is returned to position for 75 withdrawing the pin from the scarf.

If desired to use the present invention on a shirt-stud, it is only necessary to make the stem or pin shorter, and in this case the sliding collar may be dispensed with and the 80 spring only be employed to throw out one end of the cross-piece. This form of the improvement is represented in a magnified size in Fig. 3.

Under all circumstances the present improvement 85 prevents the stud or pin being stolen, because the article cannot be separated without attracting the attention of the wearer, as both hands are required, the one to turn the cross-piece into line with the 90 stem and the other to draw out the article, and there is very little risk of the article being lost, because the cross-piece normally remains substantially at right angles to the stem of the pin, stud, badge, medal, hat-pin, 95 or other article to which the improvement is applied.

It will be observed in Fig. 3 that the cross-piece C is in a vertical plane passing through the ornamental end; but the ornamental end 100 may stand in any desired relation to the pin and cross-piece.

I claim as my invention—

1. The combination with the pin having a pivoted cross-piece, of a sliding collar upon the pin passing over and holding one end of the cross-piece within the longitudinal slot of the pin and which collar allows the pin to slide through it together with the cross-piece, so that the cross-piece may occupy a transverse position and prevent the withdrawal of the pin until such cross-piece is returned to its normal position longitudinally of the pin, substantially as set forth.
2. The combination with the pin slotted longitudinally, of a cross-piece within the slot, a pivot-pin passing through the cross-piece and through the pin, and a spring con-

nected with the pin and acting to project one end of the cross-piece by turning it upon its pivot, substantially as set forth.

3. The combination with the pin slotted longitudinally and the pivoted cross-piece within the slot, of the sliding sleeve or collar adapted to hold one end of the cross-piece and the spring to project such cross-piece when liberated from the collar, substantially as set forth.

Signed by me this 6th day of October, 1898.

JOHN E. FULLER.
